MEANS FOR RESURFACING AND WIDENING
ROAD STRUCTURESWilliam H. Moseley, Springfield, Ill., assignor of
one-tenth to Samuel W. Banning, trustee,
Chicago, Ill.Continuation of application Serial No. 478,001,
August 27, 1930. This application August 2,
1933. Serial No. 633,284

10 Claims. (Cl. 94—4)

My invention relates to means for resurfacing, strengthening and widening road structures, and more particularly relates to a means of providing a substantial, practical and durable metallic side plate support for the roads where road surfacing materials are to be placed over the old road structure and extended beyond the same on each side or where the main road structure is merely to be substantially strengthened or widened on each side with materials whose top surface is on a level with the old road structure.

A further object of my invention is to provide a means of resurfacing or strengthening or widening road structures composed of concrete, brick, asphalt, wood blocks and the like, and to provide in connection with such improvements in the road a substantial and strong metallic supporting plate and channel for sustaining the weight and holding in place the road surfacing materials and road widening materials that are used, the same being in continuation of application Serial No. 478,001, filed on August 27, 1930.

I attain the objects of my invention in the device described in the annexed specification, recited in the claims and illustrated in the accompanying drawing in which like reference numerals indicate like parts in the several figures.

Referring to the drawing:

Figure 1 is a cross section of a road structure resurfaced and showing one of the forms of the side plates used for substantially supporting the road materials including the side extension thereof where the road is to be widened as well as resurfaced;

Fig. 2 is a cross section of a road construction disclosing one of the forms of supporting plates for that portion of the resurfacing materials to be used for widening the road while the road is being resurfaced;

Fig. 3 is a cross section of a type of metallic side plate adapted to rest against the side of the old road bed and upon the edge thereof and project out as a support for an extended portion of the resurfacing materials where it is desired to also widen the road;

Fig. 4 is a cross section of the channeled side plates placed along the side of the road bed as a support for a road widening surface material;

Fig. 5 is a perspective of the construction of Fig. 1;

Fig. 6 is a perspective of the construction of Fig. 4;

Fig. 7 is an inverted perspective of the construction of Fig. 1;

Fig. 8 is a perspective of an inverted part of the end of one of the side plates shown in Fig. 2;

Fig. 9 is an inverted perspective of one of the braced side plates representing a detail of the plate shown in Fig. 3;

Fig. 10 is a perspective of an inverted section of plate shown in Figs. 4 and 6; and

Fig. 11 is a perspective of a detail section showing a side plate in place on new road structure with the tie rods extending from one side plate across to the other embedded into the cement of the road slab to thus provide a substantial side support for the road surfacing materials at all times.

Referring in detail to the construction of my invention as a means of resurfacing and widening road structures, I provide in connection with the road bed 1 of integrally massed hard materials the side plates 2 and 3 shown in Fig. 1, as side supports for the extended portion of a road resurfacing material where it is desired to widen the road while resurfacing the same.

The side plates 2 and 3 are provided with integral upturned outer flanges 4 and 5 for holding the resurfacing materials substantially in place, while the lower and inner flanges 6 and 7 of the plates 2 and 3 are adapted to flank and engage the outer vertical edges of the road bed 1, which affords a continuous massive foundation for the new surface. The inner edges of the plates 2 and 3 are connected by suitably spaced tie rods 8 which extend across the road bed 1 to establish a tensile connection between these two plates.

The tie rods 8 may be substantially secured to the plates 2 and 3 either by riveting, welding, clamping or locking, or any other suitable substantial means of connecting them. The tie rods 8 will not cause objectionable ridges on the surface of the pavement, inasmuch as they will preferably be embedded in and covered by a cushioning course or an asphaltic composition 9.

For the sake of explaining the merits of my invention, I show in Fig. 1 a top surfacing course of bricks 10 which rest on the cushioning course 9. This cushioning course 9 serves the two-fold purpose of providing a leveling agent for leveling up the inequalities of the pavement and providing a proper foundation for the brick course on top.

The plates 2 and 3 may be provided with transverse ribs or flanges 11 which when located at the terminals of the respective plates may be used for establishing connection between the adjacent ends of aligned plates on the respective sides of the road.

It will be noted that the side plates 12 and 13 in Fig. 2 are similar to the plates 2 and 3 shown in Fig. 1, excepting the reinforcing bracket or angle braces 14 and 15 for providing a compression bearing for supporting the plates 12 and 13 against the sides of the road bed 1. These plates are preferably connected substantially together across the road bed 1 by tie rods 8 similar to the arrangement shown in Fig. 1.

10 It will be observed that in the event of outward strains or stresses upon the saddling or side plates of my invention they will be amply supported through the tensile strength of the tie rods 8. For instance, the tie rods 8 as observed in Fig. 1 carry a tensile strain when road stresses and strains are exerted against the plates 2 and 3. The tie rods 8 cannot give materially in their support of these stresses and they are aided by the inward gripping or clamping action of flanges 6 and 7 against the massive side walls of the road bed 1. This arrangement provides a very strong cantilever construction on the principle of a third class leverage wherein the rods 8 provide the tensile "power"; the outward and downward stress 20 on the plates 2 and 3 the "weight"; and the flanges 6 and 7 the "fulcrum".

The side plates in Fig. 3 are similar to those shown in Fig. 1 with the exception that these plates extend beyond the upturned curb or flange 30 with the idea of securing additional support from a wider range coverage of sub-grade along the road shoulder. These flanges are numbered 16 and 17 in the drawing.

Where it is desirable to widen a road structure 35 and where it is necessary to resurface the original structure, Fig. 4 illustrates a method of providing metallic supporting side plates 18 and 19. These side plates 18 and 19 are depressed so that the top of the upturned flanges 20 and 21 are level 40 with the surface 24 of the original road structure. The top portion of these plates resemble a channel and the spaces between the flanges 20 and 22 and 21 and 23 are filled with some suitable surface material such as bricks 25 and asphaltic or bituminous mixtures 26. It will be noted that in 45 this manner the surface of the widened portion of the road will then be level with the surface 24 or the original road structure, thus providing a level traffic surface over the entire expanse of completed road. It will also be noted in Fig. 4 50 that tie rods 6 are employed to join together the two outside plates 18 and 19, while they are further braced on the bottom side respectively by braces or brackets 27 and 28 which have an inward gripping or clamping action against the 55 sides of the original road structure. The principle of support used here is the same as explained above in connection with Fig. 1.

There are many thousands of miles of roads 60 originally built of concrete and other materials which have begun to crack and disintegrate to such an extent that it is necessary to resurface them in order to save them or prolong their life. When materials such as paving brick, blocks, bituminous or asphaltic mixtures are used, it is necessary to have a retaining wall or curb 65 to hold such surfacing material in place. It is frequently found desirable to widen these old road structures. In such an event it is necessary 70 to provide an adequate foundation or base for such surfacing material. My invention adequately meets both of these needs by means of a plurality of forms of steel plates which function as follows:

75 The plates are placed along both outer edges of

the road with one edge of the plate resting on the edge of the old road structure. The plates then extend on a plane outwardly and away from the edge of the road for the desired distance and have an upturned flange which acts as a retaining curb for the surfacing material. On the bottom side of the plates and extending down adjacent to and in contact with the outer edge of the old road structure are turned down flanges 6 and 7. The plates on opposite sides of the road 10 are then firmly joined together across the existing road bed by means of spaced tie rods 8 so that there can be no tendency for the plates to spread.

This construction also takes advantage of the tensile strength provided by the tie rods 8 acting 15 against the gripping or clamping action upon the sides of the road structure by the above mentioned downturned flanges, so that in the event of excessive weight occurring on the outer edge of the said plates it would be immediately checked 20 by the above mentioned forces. Additional rigidity may be given to these plates to prevent bending or sagging by means of brackets at spaced intervals, as shown in the accompanying drawing. 25

After having placed these plates, tie rods and braces in place it is a very simple matter to cover the whole road widening and resurfacing support structure with a satisfactory surfacing material which will add many years to the life of 30 the old road structure. The manner of using the metallic plates permits much easier installation and it is cheaper than constructing this extra width base and curb of concrete or other similar material, and eliminates the necessity of tying 35 the road up for traffic while the concrete is curing.

In the event it is desired to simply widen a road (see Figs. 4 and 6) and not resurface the old part, my invention provides for the plates to be formed so that they will be depressed on either 40 side of the old road structure in such a manner that when the plates are surfaced with a suitable surfacing course, they will present an even and level wearing surface flush with the original pavement. In this event it will be found necessary 45 to have these plate units firmly joined together by flat or round tie rods across the top of the old pavement, and it may be desirable to rabbet a slot or groove across the old pavement in which these tie rods would rest so that it would 50 not form a ridge or raised place in the old road portion. This method is clearly set forth in the accompanying drawing in the figures above mentioned.

Where it is desired to provide side plates for a 55 new road structure as a means of strengthening the road support and holding the same with a substantial inward grip along the sides of the base to prevent the shoulders of the road bed from more easily cracking, chipping and otherwise 60 disintegrating under stresses and strains of traffic over weakened or uneven sub-grades, the side plates 29 shown in Fig. 11 will amply meet such a need, and is held in place by tie rods 30 and 31 embedded in the pavement 1 as they extend 65 across through the road bed to connect opposite side plates at a point intermediate their outer top edges and their inner and lower edges.

It will be noted that the basic idea of the present invention resides in the provision of 70 shelf-like structures which in turn derive their main support from the foundations of the old road structure. This method of widening a road obviates the necessity of providing a new foundation structure for the road extension and at the 75

same time firmly and ruggedly co-ordinates the new surface structure with the old foundation. This results in a new road surface which is supported in part directly upon the old foundations and in part upon the shelf-like extension plates, although the new surfacing gives the appearance of a completely new road throughout.

The invention is one which utilizes to the fullest extent the value of the original road foundations, which though they may be impaired on the surface are nevertheless sufficiently massive and rugged to support the new and extended surfacing. This method of mending roads results in a great saving of materials and time and expense, and at the same time results in a road of increased surface depth and of materially greater width than heretofore.

Numerous variations in the method of utilizing the present invention are contemplated, depending more or less upon local conditions and the character of the original road which it is desired to resurface.

I claim:

1. In an invention of the class described, the combination of an old road structure of integrally massed hard materials presenting at its sides substantially plane vertical edges, metallic extension plates extending longitudinally along each of the edges of the old road structure and comprising in each instance a substantially horizontal body portion having its inner margin overlapping and resting upon the horizontal marginal surface of the old road structure and supported thereby and the remainder of the body extending outwardly from the old road structure and provided at its outer edge with an upturned marginal flange, each of the extension plates further having an intermediately disposed downwardly extending vertical flange abutting against the proximate plane vertical edge of the old road structure, means for anchoring the extension plates against lateral displacement and new surfacing material extending in uninterrupted condition over the surface of the old road structure and over the bodies of the extension plates and up to the outer marginal flanges thereof.

2. In an invention of the class described, the combination of an old road structure of integrally massed hard materials presenting at its sides substantially plane vertical edges, metallic extension plates extending longitudinally along each of the edges of the old road structure and comprising in each instance a substantially horizontal body portion having its inner margin overlapping and resting upon the horizontal marginal surface of the old road structure and supported thereby and the remainder of the body extending outwardly from the old road structure and provided at its outer edge with an upturned marginal flange, each of the extension plates further having an intermediately disposed downwardly extending vertical flange abutting against the proximate plane vertical edge of the old road structure, substantially horizontal tie rods connecting the extension plates on opposite sides of the old road structure and lying close to the surface thereof, and new surfacing material extending in uninterrupted condition over the surface of the old road structure and the tie rods and over the bodies of the extension plates and up to the outer marginal flanges thereto.

3. In an invention of the class described, the combination of an old road structure of integrally massed hard materials presenting at its sides substantially plane vertical edges, metallic ex-

tension plates extending longitudinally along each of the edges of the old road structure and comprising in each instance a substantially horizontal body portion having its inner margin overlapping and resting upon the horizontal marginal surface of the old road structure and supported thereby and the remainder of the body extending outwardly from the old road structure and provided at its outer edge with an upturned marginal flange, each of the extension plates further having an intermediately disposed downwardly extending vertical flange abutting against the proximate plane vertical edge of the old road structure, the plates being provided with transverse reinforcing ribs underlying the body and abutting at their inner ends against the downwardly extending vertical flanges, means for anchoring the extension plates against lateral displacement and new surfacing material extending in uninterrupted condition over the surface of the old road structure and over the bodies of the extension plates and up to the outer marginal flanges thereof.

4. In an invention of the class described, the combination of an old road structure of integrally massed hard materials presenting at its sides substantially plane vertical edges, metallic extension plates extending longitudinally along each of the edges of the old road structure and comprising in each instance a substantially horizontal body portion having its inner margin overlapping and resting upon the horizontal marginal surface of the old road structure and supported thereby and the remainder of the body extending outwardly from the old road structure and provided at its outer edge with an upturned marginal flange, each of the extension plates further having an intermediately disposed downwardly extending vertical flange abutting against the proximate plane vertical edge of the old structure, the plates being provided with transverse reinforcing ribs underlying the body and abutting at their inner ends against the downwardly extending vertical flanges, substantially horizontal tie rods connecting the extension plates on opposite sides of the old road structure and lying close to the surface thereof, and new surfacing material extending in uninterrupted condition over the surface of the old road structure and the tie rods and over the bodies of the extension plates and up to the outer marginal flanges thereof.

5. In an invention of the class described, the combination of an old road structure of integrally massed hard materials presenting at its sides substantially plane vertical edges, metallic extension plates extending longitudinally along each of the edges of the old road structure and comprising in each instance a substantially horizontal body portion having its inner margin overlapping and resting upon the horizontal marginal surface of the old road structure and supported thereby and the remainder of the body extending outwardly from the old road structure and provided at its outer edge with an upturned marginal flange, each of the extension plates further having an intermediately disposed downwardly extending vertical flange abutting against the proximate plane vertical edge of the old structure, means for anchoring the plates against the old road structure and adapted to prevent lateral displacement thereof, and new surfacing material extending in uninterrupted condition over the surface of the old road structure and over the bodies of

the extension plates and up to the outer marginal flanges thereof.

6. In an invention of the class described, the combination of an old road structure of integrally

- 5 massed hard materials presenting at its sides substantially plane vertical edges, metallic extension plates extending longitudinally along each of the edges of the old road structure and comprising in each instance a substantially horizontal body portion having its inner margin overlapping and resting upon the horizontal marginal surface of the old road structure and supported thereby and the remainder of the body extending outwardly from the old road structure and provided 10 at its outer edge with an upturned marginal flange, each of the extension plates further having an intermediately disposed downwardly extending vertical flange abutting against the proximate plane vertical edge of the old road structure, the plates being provided with transverse reinforcing ribs underlying the body and abutting at their inner ends against the downwardly extending vertical flanges, means for anchoring the plates against the old road structure and adapted to 15 prevent lateral displacement thereof, and new surfacing material extending in uninterrupted condition over the surface of the old road structure and over the bodies of the extension plates and up to the outer marginal flanges thereof.

- 15 7. In an invention of the class described, the combination of an old road structure of integrally massed hard materials presenting at its sides substantially plane vertical edges, metallic extension plates extending longitudinally along each 20 of the edges of the old road structure and comprising in each instance a substantially horizontal body portion having its inner margin in abutting relation to the margin of the old road structure and having a downwardly extending vertical flange abutting against the proximate plane vertical edge of the old road structure, the outer edge of the body being provided with an upwardly extending vertical marginal flange, means for anchoring the extension plates against lateral displacement and surfacing materials carried by the body portions of the extension plates and confined within the marginal flanges thereof.

- 25 8. In an invention of the class described, the combination of an old road structure of integrally massed hard materials presenting at its sides substantially plane vertical edges, metallic extension plates extending longitudinally along each of the edges of the old road structure and comprising in each instance a substantially horizontal body portion having its inner margin in abutting relation to the margin of the old road structure and

30 having a downwardly extending vertical flange abutting against the proximate plane vertical edge of the old road structure, the outer edge of the body being provided with an upwardly extending vertical marginal flange, transverse reinforcing ribs underlying the body and terminating at their inner ends in contact with the downwardly extending vertical flange, means for anchoring the extension plates against lateral displacement and surfacing materials carried by the body portions of the extension plates and confined within the marginal flanges.

35 9. In an invention of the class described, the combination of an old road structure of integrally massed hard materials presenting at its sides substantially plane vertical edges, metallic extension plates extending longitudinally along each of the edges of the old road structure and comprising in each instance a substantially horizontal body portion having its inner margin in abutting relation to the margin of the old road structure and having a downwardly extending vertical flange abutting against the proximate plane vertical edge of the old road structure, the outer edge of the body being provided with an upwardly extending vertical marginal flange, and surfacing materials carried by the body portions of the extension plates and confined within the marginal flanges thereof, and means for anchoring the extension plates in abutting relation to the old road structure and preventing lateral displacement therefrom.

40 10. In an invention of the class described, the combination of an old road structure of integrally massed hard materials presenting at its sides substantially plane vertical edges, metallic extension plates extending longitudinally along each of the edges of the old road structure and comprising in each instance a substantially horizontal body portion having its inner margin in abutting relation to the margin of the old road structure and having a downwardly extending vertical flange abutting against the proximate plane vertical edge of the old road structure, the outer edge of the body being provided with an upwardly extending vertical marginal flange, transverse reinforcing ribs underlying the body and terminating at their inner ends in contact with the downwardly extending vertical flange, and surfacing materials carried by the body portions of the extension plates and confined within the marginal flanges thereof, and means for anchoring the extension plates in abutting relation to the old road structure and preventing lateral displacement thereof.

45 WILLIAM H. MOSELEY.
